TREATMENT OF TEXTILE MATERIALS

Robert Wighton Moncrieff and Percy Henry Miller, Spondon, near Derby, England, assignors to Celanese Corporation of America, a corporation of Delaware

Application May 13, 1936, Serial No. 79,590
In Great Britain May 24, 1935

4 Claims. (Cl. 68—204)

This invention relates to the treatment of textile materials with liquids intermittently along the length of the materials. The invention is especially concerned with the intermittent liquid treatment of yarns.

For the purpose of treating yarns with a liquid intermittently along their length, the yarns may be passed in contact with wheels or drums whose peripheral surfaces consist of suitably spaced slats of appropriate widths, the slats dipping into a trough or bath of the liquid to be applied to the yarns. By such means the yarns are treated with the liquid along the parts of their length corresponding to the slats and are left untreated along the parts corresponding with the gaps between the slats. By using a wheel or drum having slats of the appropriate widths mounted at the appropriate distances from one another, the intermittent treatment of the yarns may be effected along the length of the pattern however is limited by the size of the largest wheel or drum which can conveniently be employed and, furthermore, it is necessary to provide a separate wheel or drum for each new pattern required. It is an object of the present invention to overcome these two disadvantages.

According to the present invention the apparatus for the treatment of textile materials with liquid intermittently along their length comprises a flexible base, a plurality of slats adapted to be adjustably and removably mounted on said base, and a plurality of wheels or like guiding members round which said flexible base is adapted to pass. The flexible base may conveniently consist of two or more chains or bands running parallel with each other round sprockets or wheels. The slats extend from one chain or band to the other, and the slats as well as the chains or bands are thereby maintained in parallel relationship.

By the use of the apparatus according to the present invention patterns of any desired length may be produced by adjusting the length of the flexible base and the position of the wheels or like members round which the flexible base passes. By the use of slats of different widths and by mounting and adjusting such slats in the desired manner, the pattern produced on each of the yarns treated may be of any desired character. Furthermore, the changing of the pattern mechanism to produce different patterns can be effected quickly and easily, and the expense of constructing a fresh pattern wheel for every new pattern is avoided. If necessary the

pattern may be built up two or three times or more on the patterning mechanism, especially when the desired pattern is short.

The invention is of particular advantage in the intermittent saponification of artificial yarns of cellulose acetate or other cellulose esters. Examples of other cellulose esters are cellulose formate, propionate and butyrate, and mixed esters of cellulose. Saponification is effected by the application to the yarns of a suitable saponifying agent such as caustic soda in aqueous or alcoholic solution. After the saponifying agent has been applied by the means according to the present invention, the yarns are dried and when the saponifying process has proceeded far enough the saponifying agent is washed off to check further action. The invention is also applicable to any other liquid treatment of any type of yarn such as the dyeing, mordanting, discharging or the like of yarns of cotton, wool, reconstituted cellulose or cellulose derivatives, such as the cellulose esters referred to above or cellulose ethers, e. g. ethyl and benzyl cellulose.

The apparatus may be so arranged that the yarns contact with the slats along a straight run of the flexible base, in which case it is desirable that the speed of the slats should be accurately adjusted to equal the speed of the yarn. Thus the flexible base may comprise two chains running round three pairs of sprockets, two of which are disposed higher than the third so as to form a horizontal run with which the yarns contact. The third pair of sprockets dips into a bath of the treating liquid, so that the slats, in running round these sprockets are immersed in the liquid. Alternatively, the yarns may be caused to contact with the slats at a point where they are running round a pair of sprockets.

While the invention is of the greatest convenience in the treatment of a large number of yarns side by side, e. g. in the form of a warp, it may also be applied to single yarns or to a relatively small number of yarns simultaneously. In large scale operations it may be convenient to provide two sets of patterning mechanisms for each treating bath, so that while one of the mechanisms is in use for the production of one pattern the other mechanism may be adjusted to give the pattern next required. The whole of the first pattern mechanism is then lifted out of the bath and the second pattern mechanism put in its place so that the new pattern can be proceeded with without undue delay.

By way of example forms of apparatus according to the present invention will now be de-

scribed in greater detail with reference to the accompanying drawing, in which

Fig. 1 is a plan view of a yarn treating apparatus according to the present invention;

5 Fig. 2 is a sectional side elevation of the operative part of the mechanism shown in Fig. 1; and

10 Figs. 3 and 4 are respectively a diagrammatic end elevation in section and a diagrammatic side elevation of a further form of apparatus according to the present invention.

In Figs. 1 and 2, the apparatus illustrated comprises a bath 1 adapted to contain liquid which is to be applied intermittently along the 15 length of the yarn 2 (Fig. 2). Four shafts 3, 4, 5, 6 are provided, the shaft 6 passing through gland bearings in the side of the bath 1. The four shafts 3, 4, 5, 6 each carry a pair of sprockets 7, 8, 9, 10, the sprockets 10 mounted on the shaft 6 being submerged beneath the treating liquid in the bath 1.

Around the sprockets 7, 8, 9, 10 pass two chains 11, 12 made up of plates as indicated at 13 and pins as indicated at 14 in Fig. 2. The innermost 25 plates of each chain are larger than the rest as is shown at 15, and are provided with wings 16 at right angles to the main part of the plates. Each wing is slotted as shown at 17, so that a slat 18 can be secured thereto by means of nuts 30 and bolts 19. Slat 18 are provided of various widths, and these may be adjusted in varying positions upon the wings 16 according to the position occupied by the bolts 19 in the slots 17. Other means may be adopted for adjustably securing the slats to the chain if desired. For example, the ends of the slats may be slotted instead of or in addition to the wings 16, or the wings 16 may be provided with pieces having a channel of inverted T sections, with which the head of a bolt passing through the slat 18 may be locked in any desired position by means of a nut above the slat 18. By any of these means, a chain of slats can be built up in any desired pattern, the slats being omitted altogether where a long gap is required.

45 The shafts 3, 4 carrying the sprockets 7, 8 are mounted in bearings 20 on shoes 21 which slide on rails 22 provided at each side of the bath. By these means the positions of the shafts 3, 4 may be altered and chains 11, 12 of any desired length 50 can be accommodated. The sprockets 9 mounted on the shaft 5 raise the level of the slats at the point where the yarn 2 is caused to contact with the slats.

55 In Figs. 3 and 4, a modification of the invention is shown in which three sprockets 23, 24, 25 are employed, the pair of sprockets 25 being submerged in the bath 1, while the pairs of sprockets 23 and 24 cause the chains 11 and 12 to follow a 60 horizontal run, along which the yarns 2 contact with the slats 18 carried by the chains. The sprockets are carried on shafts 26, 27, 28 mounted in a frame 29 having lugs 30 which rest on the edge of the bath 1. The shaft 27 is provided 65 with a gear 31 engaging with a gear 32 on a driving shaft 33. The whole of the frame 29, together with the shafts 26, 27, 28, the sprockets

23, 24, 25 and the chains 11, 12 may be lifted bodily from the bath by means of carrying chains 34. By these means a desired pattern can be built up outside the bath 1 while another apparatus is being employed in the bath 1, and then 5 when it is desired to change the pattern, the existing apparatus can be lifted out of the bath and replaced by the duplicate apparatus without delay.

Having described our invention what we claim 10 and desire to secure by Letters Patent is:—

1. Apparatus for the treatment of textile materials with liquid intermittently along their length, said apparatus comprising a flexible base, a plurality of slats removably mounted on and 15 slidably adjustable in relation to the length of said base, and a plurality of guiding members adapted to guide said flexible base so that said slats pass through the liquid to be applied and into contact with the textile materials. 20

2. Apparatus for the treatment of textile materials with liquid intermittently along their length, said apparatus comprising at least two chains, a plurality of slats removably mounted upon and slidably adjustable in relation to the 25 length of said chains and, in connection with each chain, a plurality of sprockets adapted to guide said chains in parallel paths and to cause the slats mounted on said chains to pass through the liquid to be applied and into contact with 30 the textile materials.

3. Apparatus for the treatment of textile materials with liquid intermittently along their length, said apparatus comprising two chains formed of plates and pins passing through said 35 plates, some of said plates being greater in size than the rest, wings on said greater plates extending at right angles thereto and parallel to the length of the chain, said wings being slotted in the direction of the length of the chain for 40 the reception of bolts, a plurality of slats removably secured to said wings by bolts passing through the slats and slots, whereby the slats are adjustable over the length of said slots, and a plurality of sprockets adapted to guide said 45 chains in parallel paths and to cause the slats mounted on said chains to pass through the liquid to be applied and into contact with the textile materials. 50

4. Apparatus for the treatment of textile materials with liquid intermittently along their length, said apparatus comprising a bath adapted to contain the liquid to be applied, a frame adapted to be removably mounted in said bath, a plurality of parallel shafts carried by said frame, 55 at least two chains, a plurality of slats removably mounted on and slidably adjustable in relation to the length of said chains and, in connection with each of said chains, a sprocket mounted on each of said shafts, said sprockets being adapted to 60 guide said chains in parallel paths so that the slats mounted on said chains pass through the liquid in said bath and into contact with the textile materials while said textile materials are passing over said bath. 65
